Filed Dec. 9, 1965, Ser. No. 392

Term of patent 14 years

(Cl. D62—4)

FIG. 1

FIG. 4

FIG. 3

FIG. 2

FIG. 5

FIG. 1 is a front perspective view of a fan housing embodying my new design;

FIG. 2 is a front elevational view of a modified form thereof;

FIG. 3 is a side elevational view thereof;

FIG. 4 is a top plan view thereof; and

FIG. 5 is a rear view of the fan housing.

The dominant features of my new design are shown in full in the drawings.

The present application in part discloses and claims subject matter disclosed in my earlier filed pending application, Ser. No. D. 82,765, filed Nov. 24, 1964, and now abandoned.

I claim:

The ornamental design for a fan housing, as shown and described.
